UNITED STATES PATENT OFFICE.

JULIUS EHRENFEUCHTER, OF HANOVER-WULFEL, GERMANY.

PARALLEL VISE.

Application filed April 14, 1919. Serial No. 290,076.

(GRANTED UNDER THE PROVISIONS OF THE ACT OF MARCH 3, 1921, 41 STAT. L., 1313.)

To all whom it may concern:

Be it known that I, JULIUS EHRENFEUCHTER, a citizen of the German Republic, and resident of Hanover-Wulfel, Germany, have 5 invented certain new and useful Improvements in Parallel Vises (for which I have filed applications in Germany, March 22, 1918, Nos. 312852, 328326; England (assigned to H. Pedersen), March 28, 1919, No. 133898; 10 Canada, April 30, 1919, No. 201422; France, April 14, 1919, No. 518145; Belgium, May 10, 1919, No. 280272; Switzerland, May 30, 1918, No. 81658; Austria, May 31, 1918, No. 80939; Hungary, June 6, 1918, No. 76-15 403; Holland, February 27, 1919, No. 5349; Italy, March 22, 1918, No. FF-105; Spain, March 22, 1918, No. 73171; Sweden, March 15, 1919, No. 5151F; Norway, March 21, 1919, No. 33252; Denmark, March 13, 1919, 20 No. 25536; Czechoslovakia, June 28, 1919, No. 1255), of which the following is a specification.

This invention relates to an improved parallel-vise of the type having a U-shaped frame and vise-jaws guided on the head-planes thereof, the novelty consisting in the particular construction of said vise.

In the accompanying drawing: Figs. 1, 2 and 3 are respectively a sectional side view, a side view, and a front view, of the improved vise, while Fig. 4 is a horizontal section of the U-shaped frame.

The integral U-shaped frame A of T-section (Fig. 4) carries on its head-planes B and C of equal level two vise-jaws D and E, which are guided thereon in dovetail fashion (Fig. 3). The front jaw D can be adjusted by a pressure-spindle F, which is rotatable in the front member of said

frame and which does not extend into the space G between the parallel lateral members thereof. The rear jaw E can be adjusted by hand and locked in position by a laterally withdrawable pawl H, which passes through a boring in said frame A and which engages in a rack I on the underside of said jaw E. The U-shaped integral frame A has rather long parallel lateral members so as to extend deeply below the axis of the spindle F and thus to afford a deep downwardly extending space G for the reception of large work-pieces in the vise, while it is provided with a hole K in its lower end (Figs. 1 and 4) for a passage of bars and rods therethrough, which are to be worked in the vise.

What I claim, is:—

A parallel-vise comprising, in combination, an integral U-shaped frame of T-section having long parallel lateral members and a passage-hole in its lower end, head-planes of equal level on said frame, a front vise-jaw and a rear vise-jaw guided on said head-planes in dovetail fashion, a rotatable pressure-spindle in the front member of said frame and engaging the front vise-jaw only, a rack on the underside of the rear vise-jaw, and a laterally withdrawable locking-pawl in said frame located to engage said rack, substantially as set forth.

In testimony whereof I have hereunto set my hand in the presence of two subscribing witnesses.

JULIUS EHRENFEUCHTER.
